(57) **CLAIM**

The ornamental design for a wearable measuring device, as shown and described.

DESCRIPTION

FIG. 1 is a perspective view illustrating a wearable measuring device;

FIG. 2 is a bottom view of the wearable measuring device;

FIG. 3 is a top view of the wearable measuring device;

FIG. 4 is a left side view of the wearable measuring device;

FIG. 5 is a right side view of the wearable measuring device;

FIG. 6 is a front view of the wearable measuring device;

FIG. 7 is a rear view of the wearable measuring device; and,

FIG. 8 is a side view of the wearable measuring device, shown in an alternate in use environment.

The broken lines of the wearable measuring device in FIG. 8 are included for the purpose of illustrating environmental structure while all other broken lines illustrate portions of the wearable measuring device; the broken lines form no part of the claimed design.
